UNITED STATES PATENT OFFICE.

ALEXANDER FISHER, OF NEW YORK, N. Y., ASSIGNOR TO FISHER PATENTS CO. INC.,
A CORPORATION OF NEW YORK.

ELECTRIC WATER HEATER.

Application filed March 22, 1922. Serial No. 545,713.

To all whom it may concern:

Be it known that I, ALEXANDER FISHER, a citizen of the United States, and resident of New York city, in the county of New York 5 and State of New York, have invented certain new and useful Improvements in Electric Water Heaters, of which the following is a specification.

My present invention relates primarily to 10 electric water heaters and more particularly to domestic installations of the type commonly known as instantaneous heaters, in which the water is automatically heated in its travel upon merely opening a faucet or 15 other outlet therefor. In the preferred application, the invention is concerned with a heater installation automatically actuated upon the opening of any of the faucets in the hot water line.

20 It is an object of the invention to provide a heater installation of simple, relatively inexpensive and compact construction, involving few parts, unlikely to become out of order and which shall be entirely automatic in its action.

Another object of the invention is to provide apparatus of the above type which can be easily and quickly installed, which shall not involve the modification or scrapping 30 of any of the parts of the standard water supply installation in domestic dwellings, and which shall consume power without waste and only while water is being delivered.

35 According to a preferred feature of the invention, my installation includes a hydraulic member automatically actuated upon release of the back pressure following the opening of a faucet, to automatically effect 40 closure of a control switch that is preferably completely enclosed against entry of dust or foreign matter and disposed out of the path of the water flow, said control switch governing the circuit to the heater element.

45 In order to effect a quick action particularly in the opening of the electric circuits while using a hydraulic switch control element of small, light and inexpensive construction, an electromagnetic system is preferably employed, the small hydraulic switch actuating a simple circuit closer, serving as a relay for controlling the circuit of an electromagnetic power switch of any appropriate design.

55 In the preferred embodiment of the in-

vention, the hydraulically operated member has a piston normally urged to closed position by a weight or the equivalent, the piston slidably in a cylinder, the latter preferably in a valve delivery casing supplied through ports in the cylinder when the piston is in switch closing position, thereby avoiding leakage difficulties. In the preferred specific embodiment, the piston is connected by a link to a rock shaft projecting from the delivery casing, the relay switch being mounted in said rock shaft.

Preferably a communicator conduit extends substantially the length of the enclosing casing from the outlet of the heat producing element, and the expansion of said conduit when heated by the water flowing therethrough is utilized as a thermostat for interrupting the relay to disconnect the source of current whenever the temperature to which the water is raised becomes excessive.

It is another object of the invention to provide an electric heater element which shall be of simple, inexpensive and compact construction, and which shall be susceptible of ready assembly.

In the preferred embodiment of heater, there is provided a cup member and a core member snugly fitting therein, the core member having preferably a helical groove in its convex surface for lodging a heating wire of cross-section smaller than the groove, the plug extending into the socket member with a snug fit, thereby closing the helical groove to form a conduit, through which the water is preferably passed in direct contact with the heating coil.

In the accompanying drawings in which is shown one of various possible embodiments of the several features of this invention,

Fig. 1 is a view in longitudinal cross-section of a preferred installation,

Fig. 2 is a sectional detail view taken along the line 2—2 of Fig. 1,

Fig. 3 is a detail section taken along the line 3—3 of Fig. 1, and;

Fig. 4 is a circuit diagram.

Similar reference characters refer to similar parts throughout the several views of the drawings.

Referring now to the drawings I have shown a heating apparatus involving a sheet metal box enclosing the various operative parts.

The box includes preferably a base 1 with integral upstanding end-walls 2 each having an inwardly extending flange 3 and a separate cover 4 formed integral with side 5 wall panels 5, the flanges 3 serving to frame said panels. The installation is connected in the water main, the water entering the installation through pipe 6' connected by union 7 at one end of the casing to inlet pipe 6'. The water is delivered from the heat producing unit by means to be described below to any of the faucets 8 in the line, through an outlet union 9 at the opposite end of the casing, threaded into a 10 bracket 10 within the casing.

Within the casing and preferably near one end thereof is a casting 11 having legs 12 as at 13 bolted to the bottom of the casing, the heat producing unit H being disposed upon a supporting platform 14 constituting an integral part of said casting, provided with an intake passage 15 and a curved delivery duct 16. The delivery duct 16 is connected for communication with the 20 outlet pipe 9, preferably by means of a communicator conduit, a brass pipe 17 preferably extending substantially the length of the casing, threaded at one end 18 into the casting 11 as at 19 and at the other as at 20 into bracket 10.

The end 21 of the intake duct is tapped to accommodate the threaded end 22 of a nipple 23 integral with a closed valve delivery casing 24, preferably supported therefrom. The inner end of intake pipe 6 is threaded at 25 into a corresponding tapped opening 26 within a valve cylinder member 27, threaded as at 28 into the side of the valve delivery casing 24. Slidable within 30 the cylinder member is a cylindrical piston member 29 having relief ports 30 in its head 31 and having a flange 32 to limit the entry thereof into the piston. The piston controls ports 33 in the side of the cylinder which 35 are opened when the same is withdrawn to the position shown in Fig. 1. The relay switch is mounted at the exterior of the valve delivery casing and comprises a pair of stationary jaw contacts 34 and a movable 40 switch contact 35 to close circuit when passed between the jaws, said contact being insulated as at 36 from a supporting arm 37. The supporting arm is preferably mounted on a squared portion of a rock shaft 38 projecting from the side of the valve delivery casing and encircled by packing 39 to prevent leakage of water. The rock shaft 38 is operated from a link member 40 within the valve delivery casing, connected at one 45 end as at 41 to the squared portion of the rock shaft, and having an elongated slot 42 at its lower end encircling a cross-pin 43 in an eye 44 formed rigid with the end of the piston. Preferably the switch supporting 50 arm 37 is formed with a tail 45 extending

rearward for a substantial distance and supporting a weight 46, adjustably secured by a set screw 47 at any point along the length of said arm. It will be seen that normally the weight will urge the rock shaft about 70 its pivot and maintain the piston 29 in port closing, and relay switch 35 in circuit opening position, while if the back pressure is released by opening a faucet the excess pressure from the mains will urge the piston to 75 port opening position and through the link 40, rock shaft 38 and switch arm 37, the relay switch to circuit closing position. Preferably a plug P is provided at the upper end of the valve delivery casing 24 to 80 permit installation of the piston and link 40 therein, to afford access thereto, whenever required.

In the preferred embodiment, the electromagnetic switch 48 is attached to one of 85 the side walls of the casing cover, preferably near the end thereof opposite that at which the heat producing element 4 is located. The electromagnetic switch is of any conventional construction including the 90 main contacts 49, bridging switch arms 50 and an actuating or holding electromagnetic coil 51^a connected in series with the relay switch across the mains + and -.

I prefer to provide a thermostat to interrupt the circuit when the temperature of the water is close to the boiling point, say about 200 degrees F. The thermostat switch includes fixed spring clip contacts 51 mounted upon an insulating support 52 preferably 100 on the bracket 10, and a coacting movable switch contact 53 on an insulating support blade 54 pivoted as at 55 upon a standard 56 also on the base lug of the bracket. The thermostat switch is normally closed and 105 as best seen in Fig. 4, will pass from between the clip contacts 51 to open the circuit by a downward impulse. As shown in the circuit diagram, the thermostat switch contact is in series with the relay switch 110 contact and only when both the relay and the thermostat are in closed circuit position is the electromagnetic switch operated. The control means for the thermostat switch includes an arm 57 having an integral upwardly extending finger 58 pivoted near its end as at 62, to the end of a bracket 63 preferably cast integral with casting 11. A cross-rod or tube 60 is supported at one end by the bracket 10 and adjustably secured thereat by nuts 61, the other end of said rod having a pin 59 extending transversely through finger 58 near the extreme end thereof. The free end of the thermostat control arm 57 extends adjacent thermostat 120 switch pivot 55 and is secured to a coil spring 64, the end 65 of which is attached to arm 54 and insulated therefrom. In the preferred embodiment, the length of the thermostat control arm is made adjustable 125

130

to permit operation, at any desired temperature. For this purpose, the thermostat control rod is preferably formed of a bar 66 rectangular in cross-section having a transverse rod 67 for accommodating an operating nut 68 extending therethrough and projecting beyond the wider faces thereof. A threaded pin 69 extends into a corresponding passage 70 in the bar and is threaded 5 into the tapped opening of the nut. It will be apparent that the length of the arm can be adjusted by simply turning the nut 68 in one or the other direction, causing the threaded pin 69 to feed inward for shortening or outward for lengthening the control bar.

The preferred form of heater unit comprises an insulating cup-shaped socket member 71 which may be of porcelain having 10 preferably a frusto-conical interior into which is fitted a corresponding frusto-conical plug member 72 in which the heating coil and water passage respectively are mounted and formed. Preferably, the plug 15 has a helical groove 73 extending about its convex surface and the electrical heating coil 74 extends in said groove, the heating coil being, however, of a cross-section materially smaller than the cross-section of the 20 groove. The plug preferably has an axial water passage 75 communicating at its upper end with the helical groove 73, the lower end of the helical groove being arranged to communicate with the outlet conduit 76. 25 Preferably, a paper or equivalent gasket 76 is interposed between the plug and the socket member, the plug fitting snugly within the socket, so that the wall of the latter will serve to bridge or cover the helical groove, 30 thereby forming a water-tight helical passage through which the water to be heated is conveyed. A cover plate 77 is secured by 35 means of tie rods 78 extending longitudinally of the cup member to firmly retain the 40 plug within the latter and to clamp the rim 45 79 of the gasket against the open end of the socket, the said cover plate having a central opening 80 for communication of the water from the curved conduit 15 to the axial water 50 passage 75. A metallic protective cap 81 is preferably passed over the socket member and has an outstanding flange 82 at its open end superposed over the plate member 77 and secured thereto by the bolts 83. The 55 terminals 85 of the electromagnet switch are joined by electrical connectors 86 to the binding posts 87 for the heater unit which are disposed at the bottom of plate 14. The 60 binding posts are connected to the ends of the heating coil by means of conducting rods 88 extending longitudinally through the plate, the cover and the length of the insulating plug, said rods being retained by nuts 89 located in recesses 90 at the upper end 65 of the insulating socket.

The nuts 91 and 92 on the ends of the tie rods 78 are disposed in recesses 93 and 94 formed in the socket member 71 and base member 77 respectively, so that the upper surface of the socket member 77 and the 70 lower surface of the cover member 77 may be brought into firm surface engagement with the metallic cup 81 and the plate member 14 respectively.

It will be seen that the circuit of the water 75 through the heater, is from conduit 75 through the helical passage 74 and out through the conduit 17 on its way to the outlet. The water thus flows directly through the helical passage in which the heating coil 80 is mounted and in direct contact with the heating coil and is thus rapidly heated.

By our preferred construction, it will thus be seen that the heating coil 74 can readily be wound in the helical outside passage 73 85 on the plug 72 and the passage is closed to form the water conduit by the mere tight frictional engagement of the plug when fitted into the socket member.

Where the heating coils are threaded back 90 and forth through a plurality of longitudinal passages in an insulating support member, it will be seen that the assembly is more difficult than in our present construction and it will further be seen that the need for 95 forming the successive bends at the connecting portions of the wire is likely to result in breaking of the coil in the course of assembly or in weakening the coil at some one or more points at which the coil may fuse 100 when put into use. Moreover, the continuous helically curved path for the water offers relatively small resistance to the flow as compared to constructions involving a water path having abrupt bends.

Heater units involving a plurality of juxtaposed insulating sections with separating gaskets between the sections are sometimes subject to leakage of water and if this difficulty is remedied by enclosure in a water 105 tight metallic casing, the danger of an electrical ground arises from contact with said casing, of water in the heater. In my construction, in which the coil enclosing element involves but two cooperating casing elements 110 with a single interposed gasket clamped or wedged tightly in place, leakage of water is avoided, as well as the danger of an electrical ground through the metallic casing, the latter, as above suggested, serving 115 mainly to protect the insulating material from breakage.

The apparatus is preferably installed in the basement of the dwelling. For this purpose, the water main is cut and the interrupted ends are simply connected one to the union 7 and the other to the union 9 and the electrical mains are connected to the conductors, marked (+ and -). Nothing further is required to complete the installation,

which can thus be performed expeditiously and at relatively small expense. The pipes and faucets in the house need in no way be modified. It will, of course, be understood 5 that the system has its main and preferred application to houses provided with both hot and cold water pipe lines.

The operation proceeds as follows: When any one of the faucets 8 on the line is 10 opened, the back pressure upon the piston 29 is removed and the forward pressure in the mains urges said piston to the outward position shown in Fig. 1, opening the ports 33 and allowing the water to pass on into the 15 valve delivery casing 24, and through the nipple 23 into the heater intake passage 15 through the central port of the heater passage, around the spiral path provided in the heater, through the outlet passage 16 in the 20 heater supporting base and thence through the communicator pipe 17 extending the length of the casing to outlet pipe 9' on its way to the faucet.

The piston in its movement to the position 25 shown in Fig. 1 has rotated the rock shaft 38, through link 40 in counterclockwise direction, against the force of the weight 46, thereby closing the relay switch 35. Thus, a circuit will be established from the mains 30 through the relay switch 35 and the thermostat switch 53 in series, to the operating coil 51 of the electromagnetic switch. The latter is, therefore, urged to closed position and current is fed to the heating wire within 35 the heat producing element, thereby heating the water passing therethrough on its way to the faucet.

When the water is heated beyond the temperature for which the thermostat is set, 40 the thermal expansion of the communicator conduit 17 through which the hot water passes caused its left end and with it the bracket 63 to move to the left to an extent sufficient to open the thermostat switch. 45 Specifically, finger 58 is moved by bracket 63 about pivot 59 as an axis, in a clockwise direction, causing the free end to move downwardly sufficiently to pass the end 56 and with it the end of spring 64 from its position above the pivot pin 55 to a position 50 therebelow, thus effecting a two-way spring action to snap the switch arm downward to the open-circuit position, apparent from Figs. 1 and 4. The relay circuit for the electromagnetic switch being now interrupted, the latter opens the heating circuit and the flow of water continues along the course previously described through the heat producing unit with the coils thereof unenergized. 55 When the temperature of the water has dropped to a sufficient extent, the contraction of the communicator conduit 17 draws the bracket arm 63 back toward the initial 60 position, thereby raising the thermostat switch actuating arm 57 and snapping the 65

thermostat switch arm back to the circuit closing position shown in Figs. 1 and 4, thereby again closing the relay circuit for the electromagnetic switch and thus again closing the main power circuit to the heat 70 producing unit.

When the faucet is again closed, the back pressure between the faucet and valve 29 builds up to equal the pressure in the water main, so that the piston is substantially in 75 equilibrium except for the force of weight 46, which rapidly urges it to closed position, thereby opening the relay switch 35 and, therefore, interrupting the main heater circuit.

Thus, the instant the faucet is opened, the electromagnetic switch is closed to set the heating coil into operation, and as soon as the faucet is closed, the electromagnetic switch opens, so that there is no waste whatsoever, the heater being energized only while the water is flowing. It will be seen 85 that the heater is economical since the coils are completely immersed in the water and substantially all of the heat generated in 90 the coil is absorbed by the flowing water.

Obviously water can pass through ports 30 and around piston 29 where there is but a small flow and small pressure differential, as in the case of a leaking faucet, the small 95 volume flow occurring without substantial movement of the piston, and without closing the switch, so that no loss of power or overheating will occur.

The thermostat will function as heretofore set forth to automatically interrupt the circuit, if the desired temperature is exceeded. Preferably, the heater unit is of such size as to generate heat at a rate sufficient to raise the water to the desired 100 temperature of 100 degrees F. when delivered at the maximum rate ordinarily encountered in practice. Theoretically, the maximum rate occurs when all of the faucets on a hot water line are open to 105 their full extent. In an ordinary one-family dwelling, no more than two hot water faucets would ordinarily be open to their full extent at the same time and, therefore, the heater unit would, in practice, be 110 made to generate heat at a rate sufficient to deliver hot water from the two fully-opened faucets. With such arrangement and in the absence of a thermostat, heat would be generated too rapidly if only one 115 faucet were turned on. However, the thermostat will function to open and close the circuit alternately, so that current would be consumed only for such fraction of the time while the faucet is open as is required 120 to heat the flowing water to the desired temperature and no higher.

Obviously, the heater unit may be made of smaller size sufficient merely to deliver water at the desired temperature from one 125

faucet at a time. In such case, of course, if two or more faucets were fully open at the same time, the water would have a lower temperature than if only one were opened. 5 On the other hand, if one faucet is opened only part-way, the thermostat will alternately open and close, as set forth above, to use current at only such rate as is required to heat the lesser quantity of water 10 flowing at any instant to the desired temperature and no hotter.

The switch actuating piston being normally held closed merely by weight 46, the hydraulic pressures on opposite sides thereof being in equilibrium, it follows that only a small pressure differential is required to move the piston, so that the apparatus will operate on low pressure as well as on high pressure water lines. Obviously, by 15 appropriate setting of weight 46, the pressure within limits may be as small as desired.

The valve delivery casing 24 completely encloses the piston 29 at all times, so that 25 packing to prevent leakage between the cylinder and the piston is not required. The only movable part projecting through the valve delivery casing is rock shaft 38. This element, however, rotates through only a 30 small angle when a faucet is opened and returns when it is closed, and does not move while the faucet is open, whether the thermostat is closed or open. The packing 35 of the rock shaft is, therefore, not subjected to noticeable wear and will have a long life.

It will be understood that the arrangement of causing the expansion of a portion of the water conduit itself to serve as the 40 thermostat actuating means is broadly applicable to apparatus embodying heating elements of constructions and for purposes other than that exemplified above.

I claim:

45 1. A water heating unit comprising a hydraulically operated member directly subjected to the pressure of the water in a main pipe, an electric heat-producing member in the path of water flow, an electric switch 50 member for controlling the circuit to said heat-producing member, and a mechanical connection between said hydraulically operated member and said switch to cause the latter to be closed automatically upon dis- 55 placement of the former, a single casing enclosing all of said elements, hydraulic connecting elements through said casing for establishing connection between the water mains and the heater unit, and electric con- 60 nections extending through the casing for establishing circuit between the electric mains and the heater, whereby said unit may be installed at any point between the mains and the outlets to heat water for delivery at 65 any of said outlets, the opening of any out-

let effecting the flow of water for actuating the motive element to close the switch.

2. A liquid heating unit comprising in combination, a casing, a conduit extending therethrough and connected between a source 70 of liquid supply and an outlet therefor, a hydraulically operated member in said conduit, an electric heat producing element in proximity to a part of said conduit, a circuit closer in said casing and out of the 75 path of liquid flow, said circuit closer being connected for operation by said hydraulic member when the outlet is open and an electromagnetic switch in said casing, said switch being controlled by said circuit closer 80 for connecting said heat producing element to a source of electric current.

3. A water heating unit comprising in combination, a casing, a water conduit extending therethrough and adapted for connection between a source of water supply and a water outlet, an electric heat producing element in proximity to a part of said conduit, a hydraulically operated member in said conduit, a circuit closer in said casing 90 and out of the path of water flow, said circuit closer being connected for operation by said hydraulic member when the outlet is open and an electromagnetic switch in said casing, said switch being controlled by said 95 circuit closer for connecting said heat producing element to a source of electric current.

4. A water heating device comprising in combination, a casing, an electric heater unit 100 therein, a conduit for conveying water to said heater unit, a conduit for conveying heated water from said heater unit, a hydraulically operated piston member in one 105 of said conduits, an electric circuit closer out of the path of water flow, a connection between said piston member and said circuit closer to operate the latter from the former, said connection including a rock shaft through said conduit and an electromagnetic switch in said casing, said switch being controlled by said circuit closer for connecting said heater unit to a source of current.

5. In an electric water heater, in combination, a casing, an electric heating unit therein, a hydraulically operated circuit closer therein, a water conduit connecting said latter elements, an electromagnetic switch in said casing and connected to be 115 operated by said circuit closer upon actuation thereof by opening of a water outlet and a thermostat switch out of the path of water flow connected for operation by the expansion of said conduit resulting from 120 the heat of the water flowing therein to interrupt the circuit when a predetermined temperature is reached.

6. The combination set forth in claim 5 in which the thermostat comprises a contact 130

controlling lever connected at one part to said conduit, whereby the expansion of said conduit relative to said fixed part will cause movement of said lever about its fulerum to 5 interrupt the circuit.

7. In an electric water heater with an automatic thermostat control, including a thermostat switch element out of the path of water flow, a control means therefor extending lengthwise of the casing, a pivotal mount therefor, an expansive element subject to the temperature of the heated water for moving said control element about its pivot, a coil spring extending lengthwise of the 10 switch arm and connected to the free end of said control arm, whereby when the water reaches a predetermined temperature, said control arm will be shifted sufficiently to cause the spring to snap the switch to open 15 position.

8. In an electric water heater, in combination, a casing, a thermostat control member therein comprising a switch member out of the path of water flow pivoted near one 20 end of the casing, a control arm therefor extending substantially the length of said casing and having an upstanding finger, fixed pivotal support means for the free end of said finger, a thermal expansive member responding to the temperature of the water 25 heated by the heater, a connection between said thermal expansive member and said finger adjacent said pivot, the free end of said thermostat control member extending adjacent 30 said switch arm, and a spring extending lengthwise of said switch arm connected thereto at one end and to the free end of said control member at the other end.

9. In an electric water heater, in combination, a casing, a casting at one end thereof, a heater supported on said casting, a bracket near the other end thereof, a delivery port through said casting, a communicating pipe connected between said 40 casting and said bracket for delivering the heated water to the outlet, a pivoted thermostat switch mounted on the base of said bracket, a horizontally extending support rod secured to said bracket, extending substantially the length of said casing, a thermostat control member having an upstand- 45

ing finger pivotally connected to said support rod, a coil spring lengthwise of said switch member, secured thereto at one end and at the other end to the free end of said 50 control member, and a bracket member movable with said communicating pipe in the expansion thereof and pivotally connected to said control member adjacent said pivot, whereby when the temperature of the water 55 in the communicating pipe rises to a predetermined degree, the bracket will shift said thermostat control bar about its pivot, causing its free end to move downward to shift the spring from one side of the thermostat 60 switch pivot to the other side thereof, thereby snapping the thermostat switch to open 65 circuit position.

10. A water heating device comprising in combination, a valve delivery casing, a cylinder 70 extending transversely of said casing, a piston movable in said cylinder, a rock shaft extending through said valve delivery casing, means connecting said piston to said rock shaft, whereby the reciprocation 75 of the former will effect a rotary motion of the latter, and an electric switch connected to said rock shaft.

11. In an electric water heater, in combination, a heating unit, a conduit for delivering heated water therefrom, and a thermostat circuit-control switch connected to said conduit to be actuated by the expansion of 80 said conduit resulting from heating the water above a predetermined temperature. 85

12. In an electric water heater, in combination, a heating unit, a conduit for delivering heated water therefrom, said conduit being fixed near one end, and a thermostat circuit-control switch out of the path of water 90 flow and provided with actuating means therefor connected to said conduit near the end opposite said fixed end to be operated by the movement of said end away from said fixed end by the expansion of the conduit 95 resulting from the flow therethrough of water above a predetermined temperature.

Signed at New York, in the county of New York and State of New York, this 21st day of March, A. D. 1922.

ALEXANDER FISHER.
